BLOUSE

Jack Orloff, New York, N. Y.

Application March 18, 1953, Serial No. 24,084

Term of patent 3½ years

(Cl. D3—25)

To all whom it may concern:

Be it known that I, Jack Orloff, a citizen of the United States of America, residing in New York, county of New York and State of New York, have invented a new, original, and ornamental Design for a Blouse, of which the following is a specification, reference being had to the accompanying drawing, forming part thereof,

Fig. 1 is a front view of a blouse showing my new design.

Fig. 2 is a rear view thereof.

Fig. 3 is an enlarged fragmentary view of a portion of the blouse illustrating the trim.

I claim:

The ornamental design for a blouse, substantially as shown.

JACK ORLOFF.
